E. F. W. ALEXANDERSON

SYSTEM OF DISTRIBUTION

Filed Nov. 1, 1924.

Inventor:
Ernst F. W. Alexanderson,
by Alexander S. Lunt
His Attorney.

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

SYSTEM OF DISTRIBUTION.

Application filed November 1, 1924. Serial No. 747,394.

My present invention relates to systems of electrical distribution, and more particularly to systems for converting direct current to polyphase alternating current.

5 One of the objects of my invention is to provide a system of the class described which will not require for its operation any devices having moving parts. A further object of my invention is to provide an apparatus for the purpose mentioned, which will be especially adapted for high voltage direct current distribution systems.

In carrying my invention into effect, I provide a plurality of single phase transformers, and supply current from the direct current source to each primary winding through a pair of electric valves. In order that these valves should operate at the best efficiency they should be controlled in such a way that current will flow only when the potential difference between the terminals is comparatively small and substantially the maximum current carried by the valve should be permitted to flow therein during the entire period during which the valve is rendered conductive. These valves may be of the pure electron discharge type, or may be of the type which operate by reason of gas ionization. In either case, the action of the valve is controlled by means of a third electrode or grid of some convenient form. In the case of the valve operating by gas ionization, it is important in order to secure good commutation of the current in transferring current from one valve to another that the current through one valve should be reduced to zero at the time it is made non-conducting and current starts in the other valve of each pair. In the case of the valve operating by a pure electron discharge, this feature is not so important, but unless the current through each valve is reduced to a small amount at the time the valve is rendered non-conducting surges may be set up in the system which will cause the insulation at some point to break down. In order to meet this requirement, I provide means whereby the potential applied to a valve is reversed at the instant that the valve is rendered non-conducting by the application of a negative potential to its grid.

The novel features which I believe to be characteristic of my invention are set forth with particularity in the appended claims,

my invention itself however, both as to its organization and method of operation will best be understood by reference to the following description taken in connection with the accompanying drawing in which I have shown diagrammatically a system for converting direct current to three-phase alternating current.

I have indicated in the drawing three pairs of valves, 1 and 2, 3 and 4, 5 and 6, of the thermionic type for supplying current from direct current mains 7 and 8, to the primary windings 9, 10 and 11, of three single-phase transformers 12, 13 and 14. The positive side 7 of the direct current system is connected to the middle point of each primary winding 9, 10 and 11, through inductive windings 15 to 20, inclusive. These windings may all be entirely independent of one another, but preferably will be wound upon a three legged closed magnetic core, windings 15 and 20 being placed on one leg, windings 16 and 17 on the second leg, and windings 18 and 19 on the third leg of the magnetic core. The windings are so connected that when equal currents are applied to the three primary windings 9, 10 and 11, the magnetomotive forces of the different windings oppose each other, thus producing no flux in the core upon which they are wound except for a slight leakage flux.

The secondary windings 21, 22 and 23 are connected in delta to the three-phase distribution mains 24, 25 and 26. Condensers 27, 28 and 29 are connected across each phase of the distribution system through transformers 30, 31 and 32. These condensers may be connected directly across the secondaries of the transformers 12, 13 and 14 or across the primary windings 9, 10 and 11. In case the valves operate by means of gas ionization the latter connection is probably preferable. The excitation for the grids of the valves 1 to 6 is obtained by means of transformers 33, 34 and 35, which are connected to the distribution mains 24, 25 and 26. The terminals of the secondaries of transformers 33, 34 and 35 are connected to the grids of the valves 1 to 6, through resistances 36. The mid points of the secondary windings are connected to the cathodes of valves 1 to 6 through resistances 37 and reactances 38. Current for heating the cathodes of valves 1 to 6, which

are all connected in parallel, may be supplied by a source of direct current 39 or from any other convenient source of current as desired.

5 In the operation of a system of the type described, it is necessary for satisfactory operation that one valve of each pair should be made conducting by the application of a positive potential to the grid before current has been interrupted in the other pair. This requires that the positive voltages applied to the grids of the valves should lead the voltages induced in the windings 21, 22 and 23. The desired lead in voltage may be 10 secured by including condensers 40 in the circuit of the primary windings of transformers 33, 34 and 35. In the arrangement shown, these condensers are connected through transformers 41 for the purpose of stepping down the current, and thus permitting the use of a smaller condenser.

The use of phase control means for the purpose of causing the current to start through one anode before it is interrupted 25 in the other is broadly claimed in a copending application of mine, Serial No. 651,409, filed July 13, 1923, and assigned to the same assignee as the present application.

In the operation of the system described, I 30 have found that although the current wave flowing through each valve is of substantial rectangular form, the potential set up in the secondary windings of the transformers is of substantially sine wave form. A substantially sine wave potential is also 35 set up across the primary windings 9, 10, 11. During the period when current is flowing through one valve the potential upon the anode of the other valve is negative 40 and of a high value, whereas the potential across the valve which is conducting is comparatively low. The difference between the positive potential of the supply main 7 and the potential of the anode of the valve 45 which is conducting is taken up by the inductive windings 15 to 20.

When the potential of the valve which is 50 non-conducting has been reduced to zero or has become positive, a positive potential is supplied to its grid. As soon as current is permitted to flow through the valve the condensers 27, 28 and 29, which have previously become charged, discharge, and as a result the potential across the valve 55 which had previously been carrying the current is momentarily reversed. This causes a sudden interruption in the current through that valve and at the same time the potential of the grid is made negative. I have 60 found therefore that the system operates in

such a way that commutation of the current is effected in a most efficient way without the production of any disturbing surges in the system.

What I claim as new and desire to secure 65 by Letters Patent of the United States, is:

1. The combination in a system of distribution of a source of direct current, a polyphase system of transformers, having their secondaries connected to a polyphase distribution system, individual connections for supplying current from said source to each of the primary windings of said transformers, an inductive winding included in each of said connections, a pair of electric 75 valves for controlling the flow of current to each of said primary windings, and means for controlling the action of said valves in such a way that when current is permitted to start in one of each pair of said valves 80 the potential applied to the other valve of the pair will be momentarily reversed.

2. The combination in a system of distribution of a source of direct current, a polyphase system of transformers, having their secondaries connected to a polyphase distribution system, individual connections for supplying current from said source to each of the primary windings of said transformers, an inductive winding included in each of said connections, all of said inductive windings being wound upon a common core, a pair of electric valves for controlling the flow of current to each of said primary windings, and means for controlling 90 the action of said valves in such a way that when current is permitted to start in one of each pair of said valves the potential applied to the other valve of the pair will be 95 momentarily reversed.

3. The combination in a system of distribution of a source of direct current, a polyphase system of transformers having their secondaries connected to a polyphase distribution system, individual connections for 105 supplying current from said source to each of the primary windings of said transformers, an inductive winding included in each of said connections, a pair of electric valves for controlling the flow of current 110 to each of said primary windings, and a capacity associated with each of said windings in such a way that when current starts to flow through one of each pair of valves the potential applied to the other valve of 115 the pair will be momentarily reversed by the action of the capacity.

In witness whereof, I have hereunto set my hand this 30th day of October, 1924.

ERNST F. W. ALEXANDERSON.
